CLAIM

The ornamental design for a curtain rod, as shown and described.

DESCRIPTION

FIG. 1 is a front, side perspective view of the curtain rod. FIG. 2 is a top, front perspective view of the design of FIG. 1.

FIG. 3 is a bottom, front perspective view of the design of FIG. 1.

FIG. 4 is a left-side view of the design of FIG. 1.

FIG. 5 is a right-side view of the design of FIG. 1.

FIG. 6 is a top view of the design of FIG. 1.

FIG. 7 is a bottom view of the design of FIG. 1.

FIG. 8 is a front view of the design of FIG. 1; and,

FIG. 9 is a rear view of the design of FIG. 1.

The curtain rod is shown with a symbolic break in its length in FIGS. 1-3 and 6-9, represented by break lines. The break lines and appearance of any portion of the article between the break lines form no part of the claimed subject matter.
